US00D732666S

(12) **United States Design Patent**
Nguyen et al.

(10) **Patent No.:** **US D732,666 S**
(45) **Date of Patent:** **** Jun. 23, 2015**

(54) **HEART VALVE PROSTHESIS**

(75) Inventors: **Than Nguyen**, Placentia, CA (US);
Hung Nguyen, Garden Grove, CA (US);
Mykim Nguyen, Santa Ana, CA (US);
Stanley Komatsu, Laguna Hills, CA (US); **Robrecht Michiels**, Laguna Hills, CA (US)

(73) Assignee: **Medtronic Corevalve, Inc.**, Minneapolis, MN (US)

(**) Term: **14 Years**

(21) Appl. No.: **29/399,122**

(22) Filed: **Aug. 9, 2011**

Primary Examiner — Ian Simmons
Assistant Examiner — Charles Hanson

(57) **CLAIM**

The ornamental design for a heart valve prosthesis, as shown and described.

DESCRIPTION

FIG. 1 is a side view of a heart valve prosthesis showing our new design;

FIG. 2 is a top view thereof; and,

FIG. 3 is another side view thereof.

The broken lines in the Figures show portions of the heart valve prosthesis which form no part of the claimed design.

1 Claim, 3 Drawing Sheets
